(57) **CLAIM**

The ornamental design for a tire as shown and described.

DESCRIPTION

FIG. 1 is a right front perspective view of a tire, showing my new design;

FIG. 2 is a left front perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof, the bottom view being a mirror image of the top view.

The broken lines depict portions of the tire that form no part of the claimed design. The dot-dash-dot lines in the figures define the bounds of the claimed design and form no part thereof.
